UNITED STATES PATENT OFFICE.

JOSEPH WILLIAM WATKINS, OF RIDGELY, TENNESSEE, ASSIGNOR OF ONE-SIXTH TO JOHN LAWRENCE VICK, ONE-TWELFTH TO GILES EARLE SULLIVAN AND ONE-TWELFTH TO RUBIE SULLIVAN, ALL OF JACKSON, TENNESSEE, AND ONE-THIRD TO WILLIAM H. VICK, OF BROWNSVILLE, TENNESSEE.

COTTON-PICKER'S SACK.

1,402,697.

Specification of Letters Patent. Patented Jan. 3, 1922.

Application filed October 22, 1920. Serial No. 418,715.

To all whom it may concern:

Be it known that I, JOSEPH W. WATKINS, a citizen of the United States, residing at Ridgely, in the county of Lake and State of Tennessee, have invented certain new and useful Improvements in Cotton-Pickers' Sacks; and I do hereby declare the following to be a full, clear, and exact description of the invention, such as will enable others skilled in the art to which it appertains to make and use the same.

My present invention relates to improvements in cotton pickers' sacks, and is intended to provide an arrangement in which there is a minimum of loss due to wear and tear on the sack.

Cotton picker sacks as now ordinarily manufactured are of considerable length and trail upon the ground when in use, with the result that sharp stones, stubble, or the like cut or rapidly wear out that portion of the sack which is on the ground.

I have endeavored to correct this defect in my Patents Nos. 1,300,065, granted April 8, 1919 and 1,317,532, granted September 30, 1919, and entitled respectively improvements in cotton pickers' sacks, in which I provide a reversible arrangement in which the sack might be turned through 180°, thus providing two surfaces for wear.

In the prior art it has been customary to use a long integral sack, with the result that if the bottom became worn out the whole sack became useless.

According to my present invention I provide a sack with an upper more or less permanent portion which is not likely to wear out except through long usage, and a detachable lower portion which may be quickly attached to or removed from the upper portion, and which may be renewed as often as desired.

Another feature of the invention is that by having the sack formed of two portions, with the lower portion detachable towards the lower end of the sack, it is feasible not only to provide a replaceable unit subjected to wear, but also to empty the sack from the middle instead of from either or both ends, as has been heretofore contemplated.

It is well known that cotton when picked in the fields tends to choke up the sack, and it requires considerable time to empty the

ordinary cotton picker's sack from either or both ends; but according to my present invention I contemplate emptying the sack from substantially the middle of the belt occupied by the cotton. 55

My present invention is further intended to provide a bag detachably connected to the lower end of the cotton picker sack proper, which may be rotated through any desired angle to take care of worn portions of the attachment, so that the attachment may be used and re-used until practically worn out 65 on all sides.

In my latest improvement in cotton picker sacks I purpose to construct the upper part of the sack of very much lighter and cheaper material than the lower part which is subjected to wear and tear, as aforesaid, and therefore I effect great economy in the operation and use of the device. 70

My invention will be more fully understood after reference to the accompanying 75 drawings, in which like parts are indicated by similar reference symbols throughout the several views, and in which:—

Figure 1 is a side elevation of the complete sack ready for use. 80

Figure 2 shows a section along the line 2—2 of Figure 1, and looking in the direction of the arrows, parts being shown on a larger scale than in Figure 1.

Figure 3 is a front elevation of the complete sack showing the flap lifted, and parts in the position for dumping from the middle of the sack; and 85

Figure 4 is a sectional view on a larger scale showing the mode of attaching the two parts of the sack together. 90

A represents the upper member of the sack which, being normally held out of the ground, is not apt to become worn except after long usage, and may be made of lighter 95 and cheaper material. The upper part of this sack may be folded or reinforced, as at a and a' and the band B is attached to the same so as to slip over the neck of the user. The sack is cut away in front, as at a^2 so as 100 to permit the convenient dropping of the cotton therein.

The lower end of the member A is provided with a flap A', which is preferably formed integral with the member A, the material being folded over, as at a^3 , to form 105

a reinforce a^4 , and the three thicknesses are sewed together, as at a^5 , (see Figure 4); the lower edge of the flap A' being folded over and sewed as at a^6 .

- 5 Attached to the reinforced portion a^4 of the sack are the tabs c supporting the fastening members C, which engage the corresponding fastening members D, secured by tabs d to the upper edge of the lower sack
10 10 E, which is preferably reinforced by folding in, as at e , see Fig. 4.

The fastening members C and D are preferably arranged so that they can be quickly and conveniently connected together, and
15 15 are so located and spaced that the loose cotton will not fall through the spaces between the fastening members.

I have shown a well known spring hook arrangement for this purpose, but I do not
20 20 mean to limit the invention to any particular fastening means, as various forms of fastening means may be adopted which will prove satisfactory in practice.

The lower member E of the sack is preferably made of heavier and stronger material than the upper member A, as this is dragged along the ground and is apt to be worn or cut by stones, stubble, or the like.

By having the fastening devices symmetrically arranged around the lower member E this member may be turned around through any desired angle so that the worn parts may be shifted outward, before the sack becomes worn through, and thus the
30 30 lower member E may be used for a long time before it becomes too worn for further use. When this member becomes so badly worn as to be unfit for further use a new member may be supplied and the old one
35 40 scrapped, or sold as junk.

It will be noted that the upper member A

and the parts carried thereby is not liable to be worn out and will not need replacing except at long intervals.

As the cotton picker gradually fills the 45 bag with cotton in the operation of picking the same, this cotton wads up in the bag and it is a troublesome operation to empty the bag from the mouth only; but by the herein described arrangement it will be sufficient 50 to unhook some of the fasteners, as shown for instance in Figure 3, and dump the contents of the bag from the middle of the bag, thus greatly facilitating and expediting the removal of the picked cotton from the bag. 55

It will be obvious that various modifications might be made in the herein-described apparatus, and in the construction, combination and arrangement of parts which could be used without departing from the spirit of 60 my invention; and I do not mean to limit the invention to such details except as particularly pointed out in the claim.

Having thus described my invention what I claim and desire to secure by Letters Pat- 65 ent of the United States is:—

A cotton picker's sack, comprising two separate members, the upper member being in the form of a tube of light textile fabric open at both ends, and provided with a neck 70 band for the operator, at the upper end thereof and an annular flap at the lower end thereof, and the lower member being in the form of a bag of heavy textile fabric open at the top and closed at the bottom, with 75 hooks and eyes for detachably connecting the lower member to the upper, and also for permitting the lateral adjustment of the lower member relative to the upper, and said flap normally closing the gap between said 80 members, substantially as described.

JOSEPH WILLIAM WATKINS.
